ALIGNING GAUGE FOR THREAD ROLLING DIES

Alfred Joachim Couto, Detroit, Mich.

Application August 15, 1949, Serial No. 110,336

3 Claims. (Cl. 33—185)

1

This invention relates to an improved screw thread rolling machine, and spacer lining gage for the dies thereof.

The screw thread rolling machine is of the character using coacting oblong dies, one of which is stationary and the other of which is movable to roll a thread on a screw blank or the like disposed between the dies. In order that the portion of the thread rolled by either die shall in all respects match and form an identical continuation of the portion of the thread rolled by the other die, it is necessary that the dies shall be initially set on the machine on longitudinal center parallel to each other; that the dies shall be leveled relative to each other to both touch the same plane throughout their length; and that the dies shall be set the proper distance apart to suit the diameter of the screw blank or other object upon which a thread is to be rolled.

The present invention therefore has as its objects to provide a machine wherein the foregoing adjustments of the dies may be readily made accurately, and wherein a gage will be provided for insertion between the dies while the adjustment thereof is being made for determining and limiting said adjustments.

Other and incidental objects of the invention will appear during the course of the following description, and in the drawings:

Figure 1 is a perspective view showing a portion of a machine embodying my improvements for adjusting the dies thereof.

Figure 2 is an end view showing my improved gage in position between the dies.

Figure 3 is a detail vertical section showing the lateral adjustment for the stationary die holder.

Figure 4 is a detail vertical section showing a typical leveling adjustment for the movable die.

Figure 5 is a detail plan view of the gage and dies.

Figure 6 is a detail elevation of the assembly of Figure 4 but without the stationary die.

Figure 7 is a detail elevation of the movable die.

Figure 8 is a detail perspective view of the gage.

In the drawings, I have shown only such portions of a thread rolling machine as are necessary to an understanding of the present improvements. The body of the machine is indicated at 10, the stationary die rest at 11, and the reciprocating ram at 12. Overhanging the ram is a guide plate 13 therefor.

The rest 11 is provided with an angle seat 14 having a flat horizontal bottom wall 15, and a flat vertical back wall 16. Mounted upon the bottom wall 15 near the forward end thereof is a pilot

stop stud 17, and adjustable on said stud is a horizontal stop screw 18.

Resting within the seat 14 is a die holder 19 for the stationary die. This holder is formed, as seen in Figure 3 of the drawings, with spaced vertical slots 20, and extending freely through said slots are bolts 21 securing the holder against the bottom wall 15 of the seat. Provision is thus made whereby, as will presently appear, the holder may be adjusted laterally toward or away from the path of the movable die, and extending through the back wall 16 of the seat to engage the holder are spaced bolts 22 for adjusting said holder laterally. Spaced stop bolts 23 are also provided and are adjustable through the back wall 16 of the seat 14 to abut the holder 19 and bind it in set position.

Formed in the stationary die holder 19 is an angle seat 24, and removably mounted at the rear end of said seat is a clamping plate 25 secured by a stud bolt 26. The holder 19 is further equipped with a removable top clamp 27 secured by a stud bolt 28.

Resting in the seat 24 of the holder 19 is a stationary die 29 limited endwise by the plate 25 which binds against the rear end of said die, while the die is held down by the clamp 27 which binds against the upper edge of the die. The die will thus be rigidly secured upon the die holder.

The movable die is indicated at 30. The mounting of this die will now be described.

Formed in the forward end of the ram 12 is an angle seat 31 in which the die 30 removably rests, and binding against the forward end of the die is a clamping plate 32 secured by a stud bolt 33. A top clamp 34 is also provided for the die and is secured by a stud bolt 35 to bind against the upper edge of the die for holding it down.

Employed in conjunction with the movable die 30 are end and center adjustments for either raising or lowering the die in the seat 31, or leveling the die longitudinally. As said adjustments are alike, a description of one will suffice for all, and in this connection reference is particularly made to Figure 4 of the drawings.

Slidable in a suitable bore in the ram 12 is a vertical tail pin 36 which extends through the bottom wall of the seat 31 to confront the lower edge of the die 30, and, if so desired, a suitable shim may be employed between said pin and the die. Slidable in a connecting transverse bore in the ram is a horizontal intermediate pin 37, and slidable in another connecting vertical bore is a vertical plunger pin 38. Screwed into the upper end of the bore which receives the pin 38 is a plug

39 coacting with said pin, while a removable plug 40 is provided at the forward end of the bore which receives the pin 37 so that the pin 37 may be installed or removed. The three pins 36, 37, and 38 are beveled to coact with each other so that, as will be seen, the plug 39 may be adjusted for either raising the pin 36 or permitting it to drop.

As seen in Figure 1 of the drawings, one of the pins 36 is arranged near each end of the seat 31 of the ram 12, while a third pin 36 is disposed midway between the other two. Thus, as will now be understood, the plugs 39 may be adjusted for raising or lowering the movable die 30 to the level of the stationary die 29. Likewise, the plugs 39 may be adjusted for either raising or lowering either end of the die 31 independently of the other end thereof and thus leveling said die longitudinally to the exact level of the stationary die 29.

At this point in the description, the relative adjustment of the two dies 29 and 30 may appropriately be noted. As previously described, the stationary die 29 is adjustable toward and away from the path of the movable die 30. Thus, the die 29 may be positioned to suit the diameter of the screw blank or other object to be disposed between the dies. The movable die 30, as also previously described, may be raised, lowered, or tilted relative to the stationary die to match the corresponding position of the stationary die.

It is now to be observed, as shown in Figure 5, that the stationary die 29 is shorter than the movable die 30. Furthermore, it is to be noted, as brought out in Figure 7, that each of the dies is provided throughout the areas of both side faces thereof with suitable threads or teeth. Thus, the dies may be reversed, edge for edge.

In conjunction with the dies 29 and 30 and the adjustments therefor, as previously described, I provide a gage for initially setting the dies.

As seen in detail in Figure 8 of the drawings, the gage includes an oblong metal block 41 of uniform width and thickness, the block being of a width to correspond with the width of the dies 29 and 30 respectively. At its end portions, the block is provided at each side thereof with threaded areas 42, and the threads of these areas are adapted to match and interfit with the threads on the side faces of the dies. Between the threaded areas 42 at each side of the block 41 is a smooth intermediate surface 43, and the thickness of the block between the surfaces 43 is the index of the diameter clearance of the object upon which a thread is to be rolled. In other words, blocks of different thicknesses will be provided, and the thickness of any given block will, as shall be explained, determine the spacing between the dies 29 and 30.

Formed in the gage block 41 from the longitudinal edges thereof are pairs of threaded sockets 44, the sockets of each pair being located near the ends of the index surfaces 43, and fashioned to be removably screwed into either pair of sockets are knurled finger pins 45 by means of which the block may be conveniently lifted and positioned. Thus, as the pins may be installed at either edge of the block selectively, the block may be reversed edge for edge to suit the inclination of the threads of the dies, depending upon whether the dies are being positioned to roll a right hand thread, in the one instance, or a left hand thread, in the other instance.

Formed in the ends of the block 41 from one longitudinal edge thereof are deep sight notches 46, and formed in the ends of the block from the opposite longitudinal edge thereof are shallow sight notches 47. These notches are of the same width, and it is now to be noted, as shown in Figure 5, that the distance between the transverse gage walls of the notches 46, or the distance between the transverse gage walls of the notches 47, corresponds with the effective length of the die 29, while the over-all length of said block corresponds with the effective length of the die 30.

In use, the dies 29 and 30 are initially positioned in the seats 24 and 31, when the movable die is, as seen in Figures 1 and 2 of the drawings, disposed opposite the stationary die. The gage block 41 is then positioned between the dies, when the dies are adjusted so that the threads on the exposed confronting faces of the dies will accurately mate with the threaded areas 42 of the block. As will be understood in view of the foregoing description, the die 29 may be moved in and out, while the die 30 may be positioned up and down, or may be tilted longitudinally to accomplish the setting of the dies. As also previously described, the index thickness of the die block will determine the spacing between the dies. Furthermore, it is to be noted that when the gage block 41 is arranged as seen in Figures 5 and 6 of the drawings, said block may, due to the presence of the sight notches 46 on said block, be conveniently disposed to register in elevation with both of the dies, or lengthwise with both of the dies, so that the dies may be set in relative longitudinal adjustment with respect to the so-called starting line of the machine, or, in other words, the line at which the work is gripped between the dies. As will be appreciated, the clamping plates 25 and 32 provide for the longitudinal adjustment of the dies. When the gage block 41 is reversed edge for edge as regards the position thereof seen in Figures 5 and 6, the sight notches 47 will, of course, serve the same purpose as just described in connection with the notches 46.

Having thus described my invention, I claim:

1. A gage for use in setting confronting threaded dies of screw thread rolling machines including an oblong gage block adapted to be disposed between said dies and of a thickness corresponding to the diameter of the object to be rolled between the dies for spacing the dies apart a distance equal to said diameter, said block being of a length corresponding to the effective length of one of the dies, and threads formed on the longitudinal side faces of the block at the ends thereof to provide threaded areas, the threads of which are adapted to mate with the threads of the dies, the block being provided at its end corners with pairs of sight notches opening through the longitudinal edges of the block and having gage walls extending at an angle to said edges, one pair of said notches opening through one longitudinal edge of the block being deeper than the other pair of said notches opening through the opposite longitudinal edge of said block and the gage walls of each pair of notches being spaced apart a distance corresponding to the effective length of the other of said dies whereby the block may be reversed edge for edge.

2. A gage for use in setting confronting threaded dies of a screw thread rolling machine, including an oblong gage block adapted to be disposed between said dies and of a thickness corresponding to the diameter of the object to be

rolled between the dies for spacing the dies apart a distance equal to said diameter, said block being of a length corresponding to the effective length of one of the dies, threads formed on the longitudinal side faces of the block at the ends thereof to provide threaded areas the threads of which are adapted to mate with the threads of the dies, the block being provided at its end corners with pairs of sight notches opening through the longitudinal edges of the block and having gage walls extending at an angle to said edges, the pair of notches opening through one longitudinal edge of the block being deeper than the other pair of notches opening through the opposite longitudinal edge of the block and the gage walls of each pair of notches being spaced apart a distance corresponding to the effective length of the other of said dies whereby the block may be reversed edge for edge, and upstanding finger pins removably fixed to one longitudinal edge of the block and adapted to be grasped for manually positioning the block, the block being provided with means whereby said pins may be fixed to the block at its opposite longitudinal edge when the block is reversed.

3. A gage for use in setting confronting stationary and movable threaded dies of a thread rolling machine including an oblong gage block adapted to be disposed between said dies and of uniform effective thickness at its end portions for spacing the dies apart a distance corresponding to the diameter of the object to be rolled between the dies, the block having parallel longitudinal edges and being of a width corresponding to the width of the dies as well as of a length corresponding to the effective length of the stationary die whereby the dies may be leveled longitudinally with respect to the block by leveling cor-

responding longitudinal edges of the dies with a corresponding longitudinal edge of the block while the block may be centered longitudinally with respect to the stationary die by registering the ends of the block with the effective end edges of the stationary die, the block being provided at corresponding end corners thereof with sight notches having corresponding gage walls extending at an angle to the adjacent longitudinal edge of the block and spaced apart a distance equal to the effective length of the movable die whereby the movable die may be centered longitudinally with respect to the block and the stationary die by registering the effective end edges of the movable die with said gage walls, and threads formed on the longitudinal side faces of the block at the end portions thereof and adapted to mate with the threads on the confronting faces of the dies when the dies are leveled longitudinally with the block.
